(57) **CLAIM**

The ornamental design for tabs on a personal respiratory protection mask, as shown and described.

DESCRIPTION

FIG. 1 is a perspective view, showing the new design for tabs on a personal respiratory protection mask;

FIG. 2 is a front view thereof;

FIG. 3 is a left-side view thereof, the right-side view being a mirror image of the left-side view;

FIG. 4 is a top view thereof;

FIG. 5 is a bottom view thereof; and,

FIG. 6 is a rear view thereof.

The dash-dot-dot line immediately adjacent the claimed areas represent the bounds of the claimed design while all other broken lines represent environmental structure and are for illustrative purposes only; the broken lines form no part of the claimed design and the shading is provided to illustrate contour only and is not an indication of texture, gloss, etc.
